UNITED STATES PATENT OFFICE.

EDWIN H. BROWN, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CONDENSING SYSTEM.

Application filed January 14, 1922. Serial No. 529,169.

This invention relates in general to improvements in the art of cooling substances, and relates more specifically to an improved system of forcing some or all of the liquid 5 propelled by a pump, through a heat transfer device such as a steam condenser or engine cooling jacket.

An object of the invention is to provide an improved cooling system especially applying 10 cable to engine driven pump units embodying a heat transfer device, which is simple in construction and economical in operation.

In the operation of steam engine driven pumps, it has heretofore been proposed to 15 utilize the liquid propelled by the pump, as a cooling medium for condensing the exhaust steam delivered from the engine. In the prior condensing systems of this type, circulation of cooling liquid through the 20 condenser has been effected in practice by means of special auxiliary pumps operated from some outside source, although it has also been suggested to merely by-pass a portion of the liquid passing the main pump, 25 through the condenser without the aid of an auxiliary pumping device. The prior auxiliary pumping devices employed to produce forced circulation of the cooling liquid, are ordinarily located in some remote portion of 30 the pumping station thereby making it necessary to provide special attendance for the auxiliary pumping devices. In cases where the auxiliary pumps are necessarily of large capacity, the power and the lubrication required to maintain proper operation, also 35 become items of considerable expense. For these reasons it is desirable to eliminate such auxiliaries wherever possible. In order to insure proper circulation of the cooling liquid in a by-pass system, it is, however, necessary 40 to employ some means other than the natural flow created by the main pump as heretofore suggested, to urge the cooling liquid through the condenser. The present invention contemplates the provision of means 45 operable by the liquid pumped by the main unit, for producing forced circulation of cooling liquid through a condenser, the operation of the means forming the subject of

an attendant. In accordance with the present invention, the forced circulation through the condenser is effected by means of one or more ejectors operable by the liquid pumped 55 by the main unit to urge more or less of this liquid through the condenser.

A clear conception of several embodiments of the invention and of the mode of operating installations embodying the same, may 60 be had by referring to the drawing accompanying and forming a part of this specification, in which like reference characters designate the same or similar parts in the several views.

Fig. 1 is a diagram illustrating a steam engine driven pumping unit having one form of improved condensing system associated therewith.

Fig. 2 is a diagram illustrating a steam engine driven pumping unit having another form of improved condensing system associated therewith.

Fig. 3 is a diagram illustrating a steam engine driven pumping unit having still another form of improved condensing system associated therewith.

In each of the units illustrated, a liquid pump 4 having a suction pipe 2 and discharge pipe 5, is connected to and is adapted to be driven by a steam engine 7 having a high pressure steam supply pipe 10 and an exhaust pipe 11 associated therewith. The exhaust pipe 11 communicates with a surface condenser 6 in which the cooling fluid and the products of condensation are separately conducted and do not mix and from which the products of condensation are delivered through a discharge pipe 12. Such delivery of the products of condensation may be effected by means of the usual pump, or by means of an automatically operated ejector. The condenser 6 is located in a by-pass which communicates with the pump suction pipe 2 by means of a cooling water supply pipe 8 and a cooling water return pipe 9. The pump 4 and engine 7 may be of any convenient type, either reciprocating or rotary, and may be either direct or otherwise connected.

In the installation illustrated in Fig. 1, the section of the suction pipe 2 located between

the cooling water supply and return pipes 8, 9, has a converging portion 3, while the portion 13 of the suction pipe 2 located beyond the return pipe 9 is formed gradually 5 diverging. The return pipe 9 communicates with the suction pipe 2 beyond the constriction formed at the junction of the converging and diverging portions 3, 13, through an annular series of relatively small orifices 14 10 which preferably extend in the general direction of flow of fluid through the suction pipe 2. This association of elements forms a liquid actuated automatic ejector operable by the suction flow and adapted to withdraw 15 cooling liquid from the condenser 6 through the return pipe 9. The cooling liquid delivered to the condenser 6 through the supply pipe 8 is withdrawn from the suction pipe 2 through an annular series of orifices 15 20 which preferably extend away from the suction pipe 2 in the general direction of flow of fluid therethrough.

In the installation illustrated in Fig. 2, the circulation of cooling liquid through the 25 condenser 6 is effected by means of an automatic liquid operated ejector 17 located in the supply pipe 8 and operable by means of high pressure liquid derived from the main pump discharge pipe 5. The ejector actuating liquid is withdrawn from the discharge pipe 5 through pipes 19, 16, and an additional high pressure liquid supply pipe 20 may be provided in order to augment the 30 circulation of cooling liquid when the normal travel of the suction flow to the pump 4 is insufficient to produce efficient operation of the ejector. The flow of liquid through the pipes 19, 20 may be controlled by means of valves which may be located in proximity 35 to the engine 7 to permit their manipulation by the engineer in charge of this engine. In this installation, cooling liquid is withdrawn from the suction pipe 2 through an annular series of orifices 15 as in Fig. 1, and is delivered 40 through the condenser 6 and the return pipe 9 by means of the ejector 17. The portion 18 of the suction pipe 2, located between the supply and return pipes 8, 9, is preferably of smaller diameter than the 45 portion of the suction pipe 2 located in advance of the supply pipe 8, while the final portion 21 of the suction pipe 2 also has decreasing cross-sectional area approaching the pump 4. By thus constructing the suction pipe 2 of gradually decreasing cross- 50 sectional area, the velocity of the suction flow is augmented as the pump 4 is approached, such increase in the velocity of flow tending to aid the delivery of cooling 55 fluid from the return pipe 9 through the annular series of orifices 22.

In the installation illustrated in Fig. 3, the structures of Figs. 1 and 2 have been 60 combined to produce an installation having a plurality of automatic liquid actuated

ejectors for creating the flow of cooling medium. The details of construction of this installation will be apparent from the foregoing description, the special advantage resulting from a combination of the structures 70 previously described, being the production of a more rapid flow of cooling medium through the condenser 6.

During normal operation of an installation embodying the present invention, the 75 suction flow created by the main pump 4 in the suction pipe 2 is partially diverted through the condenser 6 to perform the required condensing function. The quantity of liquid diverted through the condenser 80 6 may be regulated by valves suitably positioned. With the valve in the pipe 19 open, circulation of cooling medium will begin immediately upon operation of the engine 7 and pump 4, and will cease with discontinuance 85 in operation of these machines. It will be obvious that with this arrangement of elements, forced circulation of cooling medium is automatically produced and it is unnecessary to provide means other than 90 the main pumping unit itself in order to operate the circulating ejectors. The system is entirely automatic in operation and requires absolutely no attention after it has been set in operation, thereby eliminating 95 necessity of providing an attendant such as was required with the systems of the prior art.

It should be understood that it is not desired to limit the invention to the exact details of construction and operation herein described, for various modifications may occur to persons skilled in the art.

It is claimed and desired to secure by Letters Patent:

1. In combination, a pump having suction and discharge conduits, a steam engine for operating said pump, a condenser for steam exhausted by said engine, means forming 100 passages leading from one of said pump conduits to said condenser and from said condenser to said conduit, and an ejector for producing a flow of condensing liquid only through said passages and through said condenser.

2. In combination, a pump having a suction conduit, a steam engine for operating said pump, a surface condenser for steam exhausted by said engine, means forming 110 passages leading from said pump conduit to said condenser and from said condenser to said conduit, and an ejector for producing a flow of condensing liquid only through said passages and through said condenser.

3. In combination, a pump, a suction conduit for said pump, a steam engine for operating said pump, a condenser for steam exhausted by said engine, discharge and return means of communication between said suction conduit and said condenser, and a 120 125 130

fluid actuated ejector for producing a flow of condensing liquid only through said condenser and through said means.

4. In combination, a pump having a suction conduit, a steam engine for operating said pump, a condenser for steam exhausted by said engine, a by-pass from said suction

conduit passing through said condenser, and a fluid actuated ejector for urging only condensing fluid through said by-pass and for 10 returning said flow to said suction conduit.

In testimony whereof, the signature of the inventor is affixed hereto.

EDWIN H. BROWN.
